UNITED STATES PATENT OFFICE

150,469

DESIGN FOR A RAZOR RACK

Benjamin Seidel, Cleveland, Ohio, assignor of one-third to Benjamin F. Fried, Cleveland, Ohio, and one-third to Arthur P. Baumoeil, Cleveland, Ohio

Application March 11, 1947, Serial No. 137,506

Term of patent 7 years

(Cl. D4—3)

To all whom it may concern:

Be it known that I, Benjamin Seidel, a citizen of the United States, residing in the city of Cleveland, county of Cuyahoga, and State of Ohio, have invented a new, original, and ornamental Design for a Razor Rack, of which the following is a specification, reference being had to the accompanying drawing, forming a part thereof.

Figure 1 is a perspective view of the razor rack;

Figure 2 is a front elevation thereof;

Figure 3 is a top plan view; and

Figure 4 is a right side elevation thereof.

I claim:

The ornamental design for a razor rack, substantially as shown.

BENJAMIN SEIDEL.
